CLAIM

An ornamental design for a candle holder, as shown and described.

DESCRIPTION

The present invention is a candle holder that can hold burnable candles and/or associated wick structures, particularly where the candles are designed to project light and dispense actives such as insect repellents and fragrances.

FIG. 1 is a right, top, frontal perspective view of my new design;

FIG. 2 is a right side view thereof, the left side elevational view being a mirror image thereof;

FIG. 3 is a top plan view thereof; and,

FIG. 4 is a top plan view of the embodiment of FIG. 1, albeit showing the environment of surface ornamentation that optionally can be used therewith.

The broken line representations of surface ornamentation in FIG. 4, and of a recessed area on the bottom of the holder in FIGS. 1 and 2, are for purposes of illustration only, and form no part of the claim.
